FACSIMILE RECORDER

William G. H. Finch, Newtown, Conn., assignor to
 Finch Telecommunications, Inc., Passaic, N. J.,
 a corporation of Delaware

Application July 31, 1937, Serial No. 156,625

3 Claims. (Cl. 178—5)

My invention relates to facsimile systems and more particularly relates to improvements in facsimile receivers for recording pictures or messages on a continuously fed record sheet.

This invention is a continuation in part of my co-pending application, Serial No. 132,690, filed March 24, 1937, now Patent No. 2,109,109, granted Feb. 22, 1938. In this co-pending application I have disclosed novel mechanism for electro-mechanically actuating a recording stylus against a record sheet to obtain a black-white reproduction of the transmitted image.

In accordance with my present invention I contemplate employing electro-static recording to increase the recording speed and quality of the reproduction. In a preferred embodiment I employ a carbon content paper coated with a mercury oxide film and break down the film in accordance with the received picture signals impressed thereon at a high voltage in a novel manner to obtain a reproduction which has shading variations corresponding to the varying picture signal intensities.

I have discovered that by connecting a carbon content record sheet to the positive side of the picture signals and connecting the moving stylus to the negative side thereof that the film of carbon particles released from the surface of the sheet during the electrostatic breakdown action thereof will not be collected at the stylus and thereby avoiding smudging of the reproduction.

It is among the objects of my present invention to provide simplified recording apparatus for particular use in facsimile receivers to be used by laymen in the home so as to require a minimum of skill and attention to obtain results of high quality; to provide a novel high speed continuous sheet facsimile recording system employing electrostatic breakdown of a film on a sheet to render a contrasting image with respect to the color of the sheet and thereby make visible the picture to be reproduced; and to provide improved and simplified rectifier connections to the electrostatic breakdown electrode to prevent smudging of the picture.

These and further objects of my present invention will become apparent in the following description in connection with the drawing, in which:

Figure 1 is a schematic electrical diagram of a preferred arrangement for carrying out my invention and Figure 2 is an arrangement for mounting the record sheet in the recorder unit.

The picture signals are preferably generated by a facsimile transmitter system as disclosed in 55

my co-pending application Serial No. 123,770, filed February 3, 1937, now Patent No. 2,203,461, granted June 4, 1940. The signals are transmitted as a modulated carrier wave having a fundamental frequency preferably in the range of two thousand cycles per second. The method of transmitting and receiving the picture are optional and may be over land, wire or radio. For general application of the present system as a home facsimile recorder, the radio broadcasting of the signals is employed.

The receiver 10 is responsive to the channel over which the modulated audio frequency carrier picture signals are transmitted. These signals are delivered to the push-pull transformer 11 as an audio frequency carrier current modulated by the picture signals. The secondary of the transformer 11 is connected to the push-pull tetrode amplifier stage 12—12 through a potentiometer arrangement 13 for varying the output of the signals from the amplifier 12. The biasing resistor 14 is connected in series between the cathodes of the amplifier stage 12 and ground to provide suitable biasing potential for the amplifier stage. The anodes of the push-pull amplifier stage are connected to the primary of the output transformer 15. Suitable potential is applied to the anodes and screen grid electrodes of the push-pull amplifier stage 12 as indicated.

The audio frequency output from the push-pull transformer 15 is rectified by the double rectifier tube 16, the anodes 17 and 18 of which are connected to the outer terminals of the secondary of the transformer 15. The output of the rectification stage existing at the terminals 20 and 21 consists of a varying uni-potential signal. Terminal 20 connected to the center tap of the secondary of the transformer 15 is the negative potential; the terminal 21 connected to the cathode of the rectifier 16 is positive as will be understood by those skilled in the art.

The record sheet 23 is mounted in a roll 24 and is advanced past the oscillating stylus 25 line by line in accordance with the oscillation of the scanner system. A preferred manner for advancing the record sheet line by line and the structure for mounting the record sheet is described in the Patent No. 2,109,109 referred to above. The record sheet 23 is firmly gripped in position opposite the stylus 25 by means of a metal block 26 located in a region opposite the stylus 25. The sheet 23 is held against the block 26 by a flat spring 27, as described in the co-pending application referred to. The stylus 25 comprises a metallic pin which is mounted at the end of a scanner rod 28.

The rod 28 is secured at the end 30 of the vertically oscillated rod 31 by means of a set screw 32. The rod 28 is adjusted in a slot in the post 30 to maintain the point of the stylus 25 in a light contacting arrangement with the surface of the sheet 23. A spring 33 is preferably inserted between the post 30 and a collar 34 attached to the rod 28 near the stylus 25 so as to facilitate in the adjustment of the position of the stylus 25.

A source of mechanical power, such as an electric motor driven at a predetermined speed (not shown) is connected to a shaft 35 coupled to the driven shaft 36 of the scanner system through an overrunning clutch 37. The driven shaft 36 oscillates the vertical scanner shaft 31 in a predetermined manner through the schematically indicated mechanism at 38. A preferred mechanism for performing the oscillation of the scanner shaft 31 from a continuously driven shaft by means of mechanism located at 38 is also illustrated and described in detail in my Patent No. 2,109,109. The oscillation of shaft 31 causes the stylus 25 to move in the arc (defined by the radial dotted lines 39-39 as shown in Figure 2) across the record sheet 23. It is to be understood that the record sheet 23 is advanced by a distance equal to the width of the scanning line once per oscillation of the stylus 25.

The record sheet 23 of my present invention preferably consists of a paper having a high carbon content to render it conductive and having a thin film of mercury oxide coated on the sensitive surface, namely, the surface contacting the stylus 25. A voltage applied between the stylus 25 and the metallic block 26 contacting the opposite side of the paper causes an electrostatic breakdown through the paper. The portion of the record sheet across which the discharge takes place is rendered visible. In the present case, the mercury oxide film is orange in color, covering the dense black paper. When breakdown occurs, the black paper is visible through the orange coating as a black line. The degree of the marking on the paper is determined by the magnitude of the voltage and, therefore, the relative shading of the picture being transmitted is reproduced as a black-white half-tone effect on the record sheet.

The rectified picture signals are connected to the scanning system in the following manner:

The negative terminal 20 is connected to the stylus 25 through the cam switch 40 when the switch is connected to the contact 41. The cam switch contact 41 is connected to the metallic post 30 through a pigtail lead 42. The post 30 is conductively connected to the metal stylus 25 through the rod 28. The post 30 is insulated from the vertically oscillated shaft 31 and the driving system by means of an insulation piece 43, which mechanically connects the post 30 upon the rod 31. The positive terminal 21 from the rectified picture signal output is connected directly to the metal block 26 which contacts the conducting back surface of the record sheet 23. I prefer to connect the positive terminal to the ground or metallic framework of the facsimile unit. The cam switch 40 is operated against a contact 41 as illustrated during the picture signal reception period. The cam switch is operated against contact 44 during the synchronizing period to connect the rectified synchronizing signal to the synchronizing magnet relay 45 which causes the local synchronizing magnet 46 to be energized from a local power source 47. The actuation of the cam switch 40 is similar to the

actuating of the cam switch as described in my Patent No. 2,109,109 and to its actuation in the synchronizing system described in my Patent No. 2,069,061 which issued on January 26, 1937.

5 Energization of the synchronizing magnet 46 during reception of the synchronizing impulses attracts lever 48 away from the periphery of the overrunning clutch 37 and prevents it from disengaging the clutch 37. The notch 49 in the 10 surface of the stop plate of the overrunning clutch 37 would normally engage with the projection at the end of lever 48 to disengage the clutch 37 and thereby stop the scanner movement. The synchronizing impulse causing energization of the magnet 46 raises the lever 48 and 15 prevents the disengagement of the clutch 37 if the receiver is in proper synchronous and phase relation with the transmitter. This synchronizing action is also described in detail in the references referred to disclosing details of the synchronizing mechanism.

An important feature of my present invention resides in the connection of the carbon sheet proper to the metallic supporting block 26 which 25 is connected to the positive side of the rectified picture signals, and the connection of the stylus 25 which coacts with the mercury oxide coating, to the negative side of the picture signals. This 30 method of connection of the signals prevents smudging of the picture for the following reasons:

The carbon particles which result from the stylus movement over the record sheet and breakdown of the surface thereof are caused to remain 35 at the surface instead of being attracted to the stylus 25 which is placed at negative potential. The positive energization of the block 26 causes any loose carbon or other particles to be attracted to the sheet itself and prevent any adhesion thereof to the stylus 25; thus any smudging 40 of the reproduction is prevented by maintaining the stylus clean.

Although I have described the use of a carbon content sheet having an orange mercury oxide 45 coating, it is to be understood that other electrolytic-type of record sheets for electrostatic breakdown by picture signals may be employed. Thus, for black-white picture recording, a coating of barium iodide upon the white record sheet will 50 result in a black-white picture reproduction if the record sheet is passed through the scanner mechanism herein described in a damp or slightly wet condition. With the carbon content paper I have employed successful operation using picture 55 signals of the order of 400 volts average intensity and operated at 100 lines per inch at a rate of one inch per minute to produce half-tone effects of good quality.

I claim:

60 1. In a facsimile system operable on a continuous record sheet: a stylus arranged to continuously contact the record sheet; means for oscillating said contacting stylus across said sheet comprising a scanner arm attached to said stylus; and means for holding the record sheet curved in an arc about said stylus with a radius substantially that described by the stylus, said stylus being arranged to mark the inside arced surface of the sheet and adjustment means for 65 changing the pressure of said stylus against said sheet.

65 2. In a facsimile system operable on a record sheet: a scanner arranged to continuously contact the record sheet; means for oscillating said scanner, and means for holding the record sheet 70

in a position substantially perpendicular to the oscillation path of said scanner and curved in an arc about said scanner with a radius substantially that described by the scanner whereby the record sheet coacts with the oscillated contacting scanner in a substantially linear marking path on the sheet, said scanner being mounted on an oscillating arm, said arm being mounted in an oscillating means; and a spring on said arm between said scanner and oscillating means for adjusting the relationship between said scanner and said sheet.

3. In a facsimile system operable on a continuous record sheet: a stylus arranged to continuously contact the record sheet; means for oscillating said contacting stylus across said sheet comprising a scanner arm attached to said stylus; and means for holding the record sheet

in a position substantially perpendicular to all positions of said stylus and curved in an arc about said stylus with a radius substantially that described by the stylus, said stylus being arranged 5 to mark the inside arced surface of the sheet, whereby the record sheet coacts with the oscillated contacting stylus in a substantially-perpendicular relation and in a straight line marking path on the sheet to compose a facsimile of the 10 transmitted image, said scanner arm being slidably mounted on an oscillating member, said arm being slidable in a plane substantially perpendicular to that of the sheet; and means on said scanner arm between said stylus and said oscillating member for regulating the pressure of said stylus against said sheet.

WILLIAM G. H. FINCH.
